TICKET-ISSUING MACHINE.

Application filed May 21, 1925. Serial No. 31,747.

Our invention relates to means for issuing tickets in desired numbers from a strip in automatic response to the movement of a correspondingly numbered key or slide. 6 Generally speaking, our invention aims to provide a simple and compact mechanism of this general class in which the inward movement of the selected actuating member or slide automatically locks the other slides 10 against movement until the selected one is completely retracted, then feeds out the free end portion of the ticket strip, halts the feeding when the number of tickets corresponding to the designation on the slide have passed 15 a shearing member, cuts off the tickets thus fed out, and thereafter returns all parts of the mechanism to their starting positions. It also provides simple and effective means for preventing the selected actuating slide from 20 moving outward after its inward movement has been started and before its inward stroke has been completed, and for preventing a repeated inward movement of the slide after it has started its retracting movement and 25 before it has completed that movement. Furthermore, our invention provides simple and novel means for storing power during the inward stroke of any selected slide, for utilizing the stored power in effecting a quick 30 stroke of the strip-shearing cutter, and for returning the cutter to its initial position.

In our previous application No. 22,046, filed April 10, 1925 on ticket-issuing machines, we have disclosed a more complicated construction for the same general purpose, 25 namely one in which two separate levers are employed respectively for actuating the strip-feeding member and for actuating the cutting mechanism; in which sliding blocks 40 are employed for preventing the movement of slides or keys other than the selected one; in which separate means are employed in connection with each slide for preventing a reverse movement of the selected slide in either 45 direction after it has started either its inward movement or its return stroke; in which two separate springs are employed respectively for actuating the cutter and for returning it to its initial position; and in which 50 the latch for the cutter is released through the action of one of the said levers.

In our present invention, we provide pivoted latching members for locking the inward movement of all other slides after a 55 selected one has started its movement and

prior to the complete retraction of the latter, and provide a single lever for actuating both the strip-feeding member and the cutter-actuating mechanism. We also provide a construction employing only a single spring 60 in connection with the cutting mechanism, namely a spring arranged for insuring a quick movement of the cutter, and we provide cam and lever means for effecting the return of the cutter. We also provide a 65 single detent mechanism associated with the main lever of the machine for preventing a reverse movement of any selected slide intermediate of either its inward stroke or its 70 retracting stroke and provide novel means for reversing the operative position of this detent mechanism at each end of the stroke of any actuated slide.

Our present invention also provides simple and novel means for releasing the cutter at the completion of the stroke of any actuated slide, and provides a single cam member for actuating both the storing of power in the cutter-actuating spring and the returning of the cutter to its initial position. It also provides novel means for latching the strip feeder against further movement after it has fed the strip to the desired extent and prior to the cutting action, and provides novel means for latching the entire 80 machine against operation when all of the strip has been fed out. Still further and also more detailed objects will appear from the following specification and from the accompanying drawings, in which drawings 85

Fig. 1 is a perspective view of a ticket issuing machine embodying our invention and showing this when the slide designed for issuing three tickets is at the end of its inward stroke.

Fig. 2 is a plan view of the same machine with its slides in retracted position and with the top cut away.

Fig. 3 is a plan view taken from below the deck plate which supports the ticket strip and below the reel (or along the line 3-3 of Fig. 5) showing the parts in the normal or unoperated position of the machine.

Fig. 4 is an isometric view of the parts below the strip holding deck of the machine, showing the position of the parts when the slide 3 has been actuated and has started its retracting movement, with a portion of the cam member cut away to show its geared connection to the segmental gear which is con-

ected to the main lever of the machine, and with parts of the detent mechanism also cut away.

Fig. 5 is a vertical section taken longitudinally of the machine along the line 5—5 of Fig. 2.

Figs. 6 and 7 are fragmentary vertical sections taken respectively along the lines 6—6 and 7—7 of Fig. 4.

Fig. 8 is a fragmentary plan view of a corner portion of the machine, taken from the line 8—8 of Fig. 5 and showing the parts in their starting position.

Fig. 9 is a plan view corresponding to the left-hand upper corner of Fig. 2, but with the strip-supporting deck, strip guiding rollers and the strip guard omitted.

Fig. 10 is an enlarged vertical section taken through the power storing device along the line 10—10 of Fig. 9 and showing the initial positions of the two push arms and of the rocking lever.

Fig. 11 is a similar view, showing the position of these parts when the power-storing spring has been wound and the cutter is about to be released.

Fig. 12 is a similar view showing the position of the same parts after the cutter has been actuated and before the action of the cam member returns the rocking lever to its initial position.

Fig. 13 is a vertical transverse section taken along the line 13—13 of Fig. 3.

Fig. 14 is a fragmentary plan view taken from the line 14—14 of Fig. 13.

Fig. 15 is a plan view taken from below the upper guard of the reversible detent mechanism, along the line 15—15 of Fig. 13.

Fig. 16 is a similar plan view taken from below the toothed member of the reversible detent mechanism, along the line 16—16 of Fig. 13.

Fig. 17 is an enlarged plan view of a portion of this detent mechanism, showing the two guards and the toothed member in the positions occupied by them during the retracting of the main lever and the selected slide.

Fig. 18 shows the same parts during the inward stroke of the selected slide.

Fig. 19 is an elevation taken from the right hand side of Fig. 17, with portions broken away to show the assembly.

Fig. 20 is a similar elevation taken from the right-hand side of Fig. 18.

Fig. 21 is a fragmentary vertical section taken through the machine along the line 21—21 of Fig. 9.

Fig. 22 is an enlargement of an upper portion of Fig. 2, showing how the strip guard may be swung to an inoperative position when inserting a new ticket strip, and also showing the latch which locks the machine against operation when the strip is entirely consumed.

Fig. 23 is a transverse vertical section taken along the line 23—23 of Fig. 21, showing the cutter member in its initial position.

Fig. 24 is a view similar to Fig. 23 but showing the cutter member after this has cut the strip, portions of the cutter member being broken away to show the shearing plate, the adjacent strip guide and the stop lug on the cutter carrier.

Fig. 25 is a transverse vertical section taken along the line 25—25 in Fig. 9, with a portion of the cam broken away to show the pawl associated with the strip feeding reel.

Fig. 26 is a fragmentary horizontal section taken along the line 26—26 of Fig. 21, showing how the spring on the strip guard latches the strip feeder when the strip has been consumed.

In the illustrated embodiment, our machine comprises a normally locked casing, shown in Fig. 1 as having a series of slides projecting through apertures in its front wall 6, which slides are the digitally operable actuating members of our machine. These are the slides numbered from 1 to 5 inclusive, and each of them has a key by means of which the slide is adapted to be moved inwardly for issuing the number of tickets corresponding to a numeral on the key. The casing also has in its end 7 an opening through which an end portion of the ticket strip 8 is fed out, this opening being normally closed by a spring-retracted gate 93 to prevent anyone from grasping the unissued part of the strip.

The ticket strip 8 desirably has its main portion folded back and forth on itself so as to pack into a compact space as shown in Fig. 2, this strip being supported intermediate of the height of the casing by a shelf or deck 9 and being held back by a pair of riser pins 10 carried by the deck 9, so as to retain the main portion of the strip in its compacted disposition.

The issuing end of the ticket strip is guided between a pair of rollers 11 towards a rotatable strip feeder, this feeder being here shown in the form of a reel having a top 12 provided with projecting fingers 13 which are spaced to correspond to perforations formed in the ticket strip adjacent to the juncture of the consecutive tickets. A guard 14 normally holds the strip against the edge of the reel top 12 as shown in Figs. 2 and 22, this guard being desirably pivoted so that it can be swung away from the reel top as shown in Fig. 22 when a fresh ticket strip is to be inserted.

After passing the said ticket-issuing reel, the ticket strip is fed through the opening which is normally closed by the gate 93 and past a stationary shearing plate 15. This shearing plate is shown in Fig. 23 as carried by a post 16 on which the cutter member of the machine is pivoted, and the post 16 also carries a guide 17 which extends parallel to the face of the shearing plate and at a slight distance from the latter so as to keep 130

the issuing part of the ticket strip close to the shearing plate.

Thus arranged, it will be obvious that a rotating of the reel top 12 in a direction which is clockwise in Figs. 2 and 22 will feed out a length of strip corresponding to the extent to which the reel is rotated. To effect such rotation, we provide an oscillable main member which is rotatably mounted on the same 10 shaft 18 on which the reel is journaled. This member is shown in Fig. 21 as consisting of a cam 19 which carries a spring 20 continuously tending to slide a pawl or ratchet element 21 upwardly through the cam, the pawl 15 being disposed for engaging downwardly directed ratchet projections 22 on the lower plate 23 of the reel. The cam 19 is fastened to a pinion 24, driven through a reversing pinion 25 by a segmental gear 26, this gear 20 being connected through a link 27 with the operating lever 28 of the machine, as shown in Figs. 3 and 4.

The lever 28 extends transversely past the actuating members numbered 1 to 5 inclusive, 25 and each of these actuating members carries a pin 29 adapted to engage the forward edge of the lever so as to move the lever in its actuating direction when that actuating member or slide is moved inwardly. A spring 30 interposed between the lever 28 and the base frame 31 of the machine retracts the lever after it has been moved inwardly, and the lever is provided opposite each of the slides 1 to 5 inclusive with a shoulder-forming hook 33 portion 32^A which interlocks the lever with any actuated slide after the manner more fully described in our said copending application, so as to cause the actuated slide and the lever to move in unison until the slide has 40 been returned to its starting position.

For cutting off the issued portion of the strip, we provide a cutter 32, shown in Figs. 23 and 24 as fastened to a cutter member 33 which in turn is fastened to a rock-shaft 34. 45 The rock-shaft 34, as shown in Figs. 4 and 8, has a collar 35 fastened to it by a screw 36, and this collar is interlocked with one end of a spring 37 coiled about a portion of the shaft. The other end of the spring is interlocked 50 with a collar 56 loosely pivoted on the shaft, which collar carries a downwardly projecting arm 38 disposed for engaging one arm of a rocking lever 39. Adjacent to the collar which carries the arm 38, the rock shaft 34 has another collar 40 fastened to it, and this collar carries an arm 41 disposed on the opposite side of the lever arm 39 from the arm 38.

The rocking lever of which the arm 39 60 forms a portion has another arm 42 carrying at its free end a roller 43 which continuously engages the cam shaped edge of the cam 19, the roller being sufficiently small so as to enter a slot 44 which is formed in the cam (as 65 shown in Figs. 3 and 4) so as to permit the

roller-engaging edge of the cam to extend for more than 360 degrees about the axis of the cam.

When the actuating members or slides are all in their retracted or starting positions, 70 the cam 19 is in the position shown in Fig. 3, namely one in which the roller 43 is housed by the slot 44, thereby swinging the rocking lever so that its arm 39 pushes the collar arm 41 on the rock shaft of the power storing mechanism to the position shown in Fig. 10. At this time, the cutter member 33 is in the position shown in Fig. 23, namely one in which the cutter is out of the path of the ticket strip, so that the strip can freely be fed above the cutter 32 between the shearing plate 15 and the guide member 17.

When the lever 28 is moved inward, or in a direction which is clockwise in Fig. 3, the cam 19 is also moved in the same direction owing to the joint action of the link 27, and the gear members 24, 25 and 26. Consequently, the sloping cam edge 45 which forms the inner wall of the slot 44 will press against the rocking lever to rock the latter in a direction which is also clockwise in Fig. 3, thereby moving the collar arm 38 from the position of Fig. 10 to that of Fig. 11. Since the collar associated with this arm 38 is interlocked with one end of the coiled spring 37, the resulting movement will tend to rotate the spring bodily and hence would rotate the rock-shaft 34 with which the other end of the spring is connected through the collar 35. However, this rock-shaft 34 has the cutter member 33 fastened to it and the cutter member has a projecting finger 46 which underhangs a spring pressed latch 47 at that time, as shown in Fig. 23. Consequently, this latch will prevent a rotation of the rock shaft, so 95 that the movement of the rocking lever and the corresponding movement of the collars on the shaft from the position of Fig. 10 to that of Fig. 11 only serves to tension the spring 37 until the latch 47 is released. As soon as this releasing occurs, the power stored in the spring rotates the cutter-carrying rock shaft and swings the cutter member 33 to the position shown in Fig. 24. In moving to this latter position, the cutter 32 cooperates 100 with the shearing plate 17 in cutting off the issued part of the ticket strip, and the actuating of the cutter through the spring in which power has previously been stored insures a quick and clean cutting action.

To release the cutter-restraining latch 47 at the proper time, we form this latch as one end of a pin 49 which is slidably supported on the base plate 31 of the machine in a fork 50 and which is connected by a link 51 to a pin 52 projecting from a trip shaft 53. This trip shaft extends transversely of the actuating or slide members and has fastened to it a series of downwardly projecting pins 98 each 115 of which extends down adjacent to a side 120 125 130

of one of the actuating slides. Each slide has a lateral projection 54 disposed for engaging the trip shaft pin 98 which is adjacent to it, the projections 54 being disposed so that the said engagement will occur for each slide when that slide has almost completed its inward stroke. When this engagement occurs, the continued inward movement of the actuated slide rocks the trip shaft 53 so as to retract the stem 49 which has the latch 47 at one end, the rocking of the shaft being in opposition to a spring 55 which turns the shaft in the opposite direction as soon as the inward pressing movement on the actuated slide is released.

Each of the actuating slides extends through perforations in a riser 57 near the front of the machine and in another riser 58 behind the trip shaft 53. To prevent the slides from being jarred out of their normal inoperative positions, we provide a spring member 58^B which has a grooved top normally overhanging the upper ends of the pins 29 on all of the slides so as to latch the slides yieldingly in their starting positions. This latching member 58^B is here shown (Fig. 7) as fastened conjointly with the forward guide riser 57 to the base plate 31 of the machine.

To prevent other slides from being moved after any selected slide has started its actuating movement and before the selected slide has been completely retracted, we provide a series of pivoted latches, shown in Figs. 3 and 4 as numbered from 59 to 62 inclusive and as pivoted to the top of the rear guide riser 58. Each of these latches is pivoted at a point between two of the slides and is formed so that its swinging movement will be limited by engagement with the top of the riser 58 to positions in which it will only permit one of the adjacent slides to be moved past the latch. The adjacent latches are also formed so as to abut against each other, thereby causing a rocking of any one latch to rock the adjacent latches also, and each latch has a pair of fingers 63 respectively so disposed as to be in the path of the two adjacent slides when the latch is in its medial position as shown in Fig. 3. As soon as one of the slides is started on its inward or actuating movement, as shown in Fig. 4 for the slide 3, its rear end (which is rounded or tapered for that purpose) engages downwardly projecting arms 63 on the two adjacent latches and rocks these latches away from each other to permit the actuated slide to pass between these latches, as shown in connection with the latches 60 and 61 in Fig. 4. In doing so, each of these last two named latches also swings the next adjacent latch out of its medial position, or from the position of Fig. 3 to that of Fig. 4. Consequently, all except the selectively actuated slide have the stop fingers 63 on one or more of the pivoted latches disposed in its path, so that these fingers will

prevent an inward movement of the other slides, since engagement of the actuated slide with the edges of the stop fingers 63 of the latches adjacent to it cooperates with the engagement of the riser 58 by the two end-most latches to prevent all of the latches from being moved about their pivotal mountings. However, when the actuated slide has been completely retracted, the latches are again free to move until some one of the slides is again started in its inward direction.

To compel an uninterrupted movement of the actuated slide in each direction, we provide a single and reversible detent mechanism which is associated with the main lever 28, the latter being interlocked during the movement of any selected slide through the previously described engagement of the pin 29 on that slide with the adjacent hook 32 on the said lever. This detent mechanism includes a stationary rack plate 64 supported above the base frame 31 of the machine by posts 65 and having a toothed edge 66 curved concentric with the pivot 67 on the main lever 28 as shown in Fig. 4. Pivoted upon a post 67^B which is fastened to the lever 28 are a pair of pawls 68 and 69 which extend obliquely in opposite directions from the lever 28 so that they can engage the toothed edge 66 of the rack plate to resist a movement of the lever in respectively opposite directions. A spring 70 continuously tends to swing both of these pawls into engagement with the toothed rack edge, but one or the other of these pawls is also held away from this toothed edge 66 by a smooth-edged guard along which the inoperative pawl can slide freely. With this in mind, we form the two pawls so that the pawl 68 has its tooth-engaging free end extending above the toothed member 64 and disposed for engaging the smooth curved edge of a guard 71, while the free end of the companion pawl 69 is disposed for engaging the curved and smooth edge of a lower guard 72. Each of these guards is slidably mounted on the rack plate 64 so as to be movable from a position in which its smooth guard edge is disposed back of the teeth 66 to a position in which this edge extends further towards the pivot axis of the lever 28 than these teeth. For this purpose, we are showing the upper guard 71 as having a pair of slots 73 oblique to the lever 28, and are showing the rack plate 64 as carrying a pair of riser screws 74 each of which extends through one of the said oblique slots. The toothed rack plate 66 also carries a pair of downwardly extending screws 75 each of which extends through a slot in the lower guard 72, but the slots in the latter are sloped in the opposite direction from the slots 73 in the upper guard. One of the guards, namely the lower guard plate 72 in Fig. 4, carries a pin 96 which is slidable in a slot 97 on the upper guard, thereby causing each guard to

be moved longitudinally in unison with the other guard.

When the lever is in its retracted or starting position of Fig. 3, the upper guard 71 is in an operative position in which it holds the upper pawl 68 away from the toothed edge 68, while the lower guard 72 is drawn back so as to permit the lower pawl 69 to engage the teeth of the rack. Thus disposed, the 10 spring 70 permits the pawl 69 to ride over the teeth of the rack, so that this pawl will not interfere with the continued inward movement of the lever and of the actuated slide.

However, if the operating pressure on the 15 selected slide is released before that slide has completed its inward stroke, the pawl 69 will engage the rack tooth adjacent to it and hence will prevent a retraction of the lever 28 by the retracting spring 30.

20 When the power stored in the spring 37 of the power storing mechanism is actuating the cutter by moving the cutter member from the position of Fig. 23 to that of Fig. 24, the cam arm 76 on the cutter member 25 engages an arm 77 which is fastened to a rock shaft 78. This shaft 78 has at its other end an arm 79 connected by a link 80 to a 30 detent 81 which is pivoted on the rack plate 64 and which has at one end a finger 82 disposed so as to abut against the inner end 35 of the upper guard 71 when the latter is in the position of Fig. 3. When thus disposed, the detent prevents both guards from being slid inwardly of the machine by a tension spring 82^B which is interposed between the rack plate 64, and the pin 96 which cooperates with the slot 97 in transmitting a longitudinal movement of one guard to the other. The 40 rocking of the shaft 78 through the said action of the cam 76 on the cutter member draws the link 80 inwardly of the machine, thereby swinging the detent 82 to its inoperative position of Fig. 4 and permitting the spring 82^B to draw both of the guards 71 and 72 45 inwardly of the machine or towards the left in Fig. 3. When thus moved longitudinally, the inclination of the slots 73 in the upper guard cause this guard to move back of the rack teeth to the position shown in Fig. 4,

50 while the oppositely directed inclination of the slots 83 in the lower guard 72 cause the latter to move forward. Consequently, the lower pawl 69 is then held out of operative engagement with the rack, as shown in Fig. 55 17, while the upper pawl 68 engages the rack and permits a free retracting movement of the lever 28 but prevents a repeated inward movement of this lever before the lever has completed its retraction.

60 When the cutter member is returned to its initial position through the operation of the cam member 19 and the rocking lever associated with the latter, it releases the pressure of the cam finger 76 on the shaft arm 77 of 65 Figs. 23 and 24, thereby permitting a spring

84 to swing the detent 81 in a direction which is clockwise in Fig. 4. However, this occurs after the spring 82 has moved the guard 71 toward the left in Fig. 4, thereby disposing the inner or left-hand end of this guard (in 70 Fig. 4) in the path of the finger 82 of the detent, so as to prevent the latter from returning to its initial position of Fig. 3. While completing its retracting movement, the main lever 28 engages a downwardly projecting finger 85 on the lower guard 72, thereby drawing this guard forwardly of the machine or to the right in Figs. 4 and 13 against the resistance of the spring 82. When doing so, the pin and slot connection 96 and 97 between the two guards causes the upper guard to be drawn in the same direction, thereby permitting the detent 81 to return to its initial position of Fig. 3. Hence the single rack serves in connection with the two pawls 68 85 and 69 for insuring a complete stroke of the main lever and of the selected slide in each direction, thereby preventing reciprocatory intermediate movements, and the rack and pawl arrangement is automatically shifted as 90 to its operative direction at the completion of each stroke of the lever.

Whenever our machine is operated, the cam 19 (Fig. 3) is rotated to an extent proportioned to the number of tickets which are to be issued and a corresponding movement is imparted to the rotatable ticket feeder through the ratchet engagement between the spring-pressed pawl 21 on the cam and the teeth 22 on the ticket feeding reel. However, the momentum imparted to this reel may tend to rotate it beyond the intended extent and hence might cause it to feed the ticket strip beyond a point where the cutter is opposite the juncture of two tickets. To avoid this, 100 we provide a feeder latch which engages the reel just before the cutter is actuated, so as to halt the reel at the end of the intended feeding movement and until the actuated slide has started its retracting movement. A latch 105 for this purpose is shown at 92 in Figs. 3 and 8 as pivotally mounted and normally held away from the lower plate 23 of the reel by a spring 93. This latch also has a rigid arm 91 carrying a pin which extends through an 110 elongated slot in a link 90, the other end of which link has a slot engaging a pin 89 on the trip shaft 53. When this trip shaft is rocked, the elongation of the slot in the link 51 fastened to the cutter latch prevents this link 115 from immediately moving that latch. But the initial rocking of the trip shaft tensions a spring 94 interposed between the link 90 and the arm 91 of the reel latch and hence swings the latch 92 from its initial position 120 (shown dotted in Fig. 8) to its holding position (shown in full lines in Fig. 8), so that the tip of this latch will be engaged by the next finger 100 on the reel to prevent a further 125 rotation of the reel. Then, owing to the said 130

elongation of the link slot, the cutter latch is released a little later, or after the strip feeder has been positively halted in a position in which the engagement of one of the reel fingers 100 with the latch 92 brings the juncture of two tickets opposite the cutter. As soon as the actuated slide starts its retracting movement, the spring 55 turns the trip shaft 53 back to its starting position and hence 10 causes the link 27 to force the feeder latch 92 back to its inoperative position.

The top plate 12 of the reel which serves as a ticket feeder also desirably has perforations 101 arranged in a circle (as shown in 15 Fig. 22) so that the teeth of a pinion 87 can mesh with the spaces between them, thereby turning the shaft 102 of a counter 88 which registers the total number of tickets issued. To prevent this counter from being operated 20 through an actuating of a slide when the ticket strip is exhausted, we mount on the strip guide 14 a spring finger 103 which has a bent end normally bearing against the outer face of the ticket strip and which has a longitudinal slot back of this bent end. When the ticket strip has been entirely fed out, the resiliency of the spring finger 103 causes its bent end to snap over the edge of the top plate 12 of the reel, so as to bring the end of the 25 said slot into the path of one of the fingers 13 on this top plate, as shown in Fig. 26. This slot end then halts the reel and operates through the ratchet engagement between the reel and the cam 19 to prevent rotation of the 30 cam. Since the cam is positively connected through the link 27 to the main lever 28, this also is then latched against movement, so that the entire machine is effectively latched against operation until a fresh ticket strip 40 has been inserted with a portion of it disposed between the reel top 12 and the spring finger 103.

However, while we have illustrated and described our machine in an embodiment including various highly desirable shapes and arrangements of different parts, we do not wish to be limited as to these, since the details of construction and arrangement might obviously be modified in many ways without departing either from the spirit of our invention or from the appended claims. Neither do we wish to be limited to the use of the various novel features of our invention in conjunction with one another, or to the use of our invention in machines in which the issued strip is imprinted to form tickets.

We claim as our invention:

1. In a ticket issuing machine, a plurality of reciprocable and interchangeably operable actuating members, and means for locking all except the selectively moved actuating member against movement until the selected one has returned to its starting position; the said means comprising pivoted latches disposed between the consecutive actuating

members and behind the rear ends of all thereof when the actuating members are in their starting positions, the consecutive latches having arms abutting against one another, and stops for limiting the rocking movement of the latches about their pivots, the spread of the arms and the disposition of the stops being such that the separational movement of any two latches by the passing of a part of an actuating member between them will dispose the other latches so as to prevent the movement of any other latching member between any two of the said other latches. 70

2. In a ticket issuing machine, mechanism as per claim 1, and a pair of supporting members through which all of the actuating members slidably extend, the more rearward supporting member having the said latches pivoted on it and having portions adapted to engage the latches to afford the said movement limiting stops. 80

3. In a machine for issuing portions of a strip, a rotatably mounted strip feeder, actuating means including a rotatable member coaxial with the strip feeder and connected to the latter by a ratchet connection, a strip cutter, spring means tensioned by the said actuating means during the actuating of the feeder and connected to the cutter, a cutter latch for preventing operation of the cutter by the spring means during the feeding of the strip, feeder halting means associated with the actuating means for latching the feeder against continued movement when the strip has been fed to the desired extent, trip means associated with the actuating means for releasing the cutter latch subsequent to the said halting of the reel, and connections for thereafter retracting the feeder halting means and returning the cutter latch to its operative position. 90

4. A strip issuing machine as per claim 3, in which the said connections include a member reciprocated by the actuating means and connected to the feeder halting means by a spring, the said member having a lost motion connection to the latch to permit the spring to actuate the feeder halting means prior to the releasing of the latch. 105

5. A strip issuing machine as per claim 3, in which the cutter is mounted on a cutter carrier and in which the said connections include a rock shaft and an arm fast on the rock shaft and disposed to be engaged by the cutter carrier during the cutting movement of the cutter. 115

6. In a strip-issuing machine, a strip feeder, a strip cutter, mechanism for storing power for actuating the cutter, a plurality of manually operable actuating members, connections whereby any operated actuating member operates the strip feeder and stores power in the said mechanism, a latch for preventing the said mechanism from operating 120

the cutter; and releasing means actuated by the selected actuating member, subsequent to the operation of the feeder and to the storing of the power, for releasing the latch; the releasing means including a rock shaft having arms respectively adjacent to the several actuating members, each actuating member having a portion adapted to engage the shaft arm adjacent to it.

7. In a machine for issuing a strip to a varying extent, a strip feeder, operating means for actuating the strip feeder selectively to the desired extent, a strip cutter, and mechanism for actuating the cutter and thereafter returning the cutter to its starting position; the said mechanism including a rocking lever and a cam engaging one end of the lever, the cam having an eccentric portion adapted to actuate the lever in one direction while the operating means are actuated to the minimum strip issuing extent and having a portion concentric with its axis and in continuation of its said eccentric portion to permit a further movement of the cam without imparting further motion to the lever.

8. In a machine for issuing a strip to a varying extent, a strip feeder, operating means for actuating the strip feeder selectively to the desired extent, a strip cutter, and mechanism for actuating the cutter and thereafter returning the cutter to its starting position; the said mechanism including a rocking lever and a cam engaging one end of the lever, the cam having an eccentric portion adapted to actuate the lever in one direction while the operating means are actuated to the minimum strip issuing extent and having an arm adjacent to but spaced from the said eccentric portion to draw the adjacent lever end towards the axis of the cam during the retracting movement of the cam.

45 9. In a machine for issuing portions of a strip, operating mechanism including a reciprocal lever, manually operable means for moving the lever in its operating direction, and spring means for retracting the lever; a stationary rack adjacent to and transverse of the lever, detent means carried by the lever and arranged for engaging the

40 10. rack to prevent a repeated movement of the lever in its operating direction after the lever has started its retracting movement and before it has completed its retraction, a movably mounted guard adapted when in one position to render the said detent means inoperative, and yielding means for holding the guard out of its said position during the retracting movement of the lever, the lever being disposed for engaging a portion of the guard substantially at the end of its retracting movement so as to move the guard against the resistance of the said yielding means and into its said position.

10. In a machine for issuing portions of a
65 strip, a strip feeder, a cutter arranged for

cutting off the fed portion of the strip, a reciprocal operating lever, connections whereby the lever successively actuates the feeder and the cutter, a stationary rack having teeth extending adjacent to and transverse of the lever; two detents movably mounted on the lever and both disposed for engaging the rack, the first detent being adapted when engaging the rack to prevent a retracting movement of the lever, the second detent being adapted when engaging the rack to prevent movement of the lever in its feeder actuating direction; means responsive to the actuating of the cutter for rendering the first detent inoperative, means operated by the lever at the end of its retracting stroke for rendering the second detent inoperative, and means for making each detent operative when the other detent is rendered inoperative.

11. The combination with a reciprocable lever, of an arcuate rack adjacent to the lever, two spring-pressed pawls carried by the lever and both adapted to engage the rack, a pair of arcuate guards each movable into and out of a guarding position in which it holds one of the pawls out of engagement with the rack, and means connecting the two guards whereby a movement of either guard out of its guarding relation to the pawl with which it is associated moves the other guard into guarding relation with respect to the other pawl.

12. The combination with a reciprocable lever, of an arcuate rack adjacent to the lever, two spring-pressed pawls carried by the lever and both adapted to engage the rack, a pair of arcuate guards each movable into and out of a guarding position in which it holds one of the pawls out of engagement with the rack, and means associated with the two guards and actuated by the lever substantially at the end of each stroke of the lever for moving the guards so that each guard is only in its guarding position while the lever is moving in one direction. 100 105 111

13. Mechanism as per claim 11, in which each of the guards is mounted for slidable movement obliquely transverse of the rack, the obliquity being in reverse direction for the two guards. 115

*14. The combination with a reciprocable lever, of an arcuate rack adjacent to the lever, two spring-pressed pawls carried by the lever and both adapted to engage the rack, a pair of arcuate guards each movable into and out of a guarding position in which it holds one of the pawls out of engagement with the rack, means for simultaneously moving the guards longitudinally of the rack, and connections between the guards for causing such longitudinal movement thereof to shift the previously operative guard out of its guarding position and to bring the previously inoperative guard into an operative guarding position.

15. Mechanism as per claim 14, in combination with spring means continuously urging the guards into a position in which a certain guard is operative while the other guard is
5 inoperative, means actuated by the reciprocable member substantially at one end of its stroke for moving the guards to the reverse position against the resistance of the spring, a latch for holding the guards in their said
10 reverse position, and means responsive to the approaching of the lever to the other end of its stroke for releasing the latch.
16. The combination with a stationary rack, of a reciprocable member having a
15 portion adjacent to the teeth of the rack, a pair of pawls movably mounted on the said member and both disposed for engaging the teeth of the rack and respectively adapted to prevent movement of the said member in opposite directions, two guards both mounted
20 for movement transversely of the rack and each adapted when in one position to hold one of the pawls out of engagement with the rack, and means for simultaneously moving the guards in opposite directions transversely 25 of the rack so as to alternate the operative disposition of the two guards.
17. Mechanism as per claim 16, in which the guard moving means are disposed so as to be actuated by the reciprocable member at 30 each end of its stroke.
18. Mechanism as per claim 16, in which the guard moving means are disposed so as to be actuated by the reciprocable member at each end of its stroke, and in which the 35 disposition is such that the actuating of the said means at the end of one stroke is effected by direct engagement of the member with one of the guards.

Signed at Chicago, Illinois, May 16th, 1925.

JAMES S. ARCUS.
